(57) CLAIM

The ornamental design for a shopping cart frame and basket assembly having a lowered center of gravity, as shown and described.

DESCRIPTION

FIG. 1 is a front, right perspective view of a shopping cart frame and basket assembly having a lowered center of gravity showing our new design;

FIG. 2 is a right side elevation view thereof, the left side view being identical to the right side view;

FIG. 3 is a top plan view thereof;

FIG. 4 is a bottom plan view thereof;

FIG. 5 is a front elevation view thereof; and,

FIG. 6 is a rear elevation view thereof.
